UNITED STATES PATENT OFFICE

2,136,249

REFRIGERANT EVAPORATOR

Delbert F. Newman, Schenectady, N. Y., assignor
to General Electric Company, a corporation of
New York

Application April 17, 1937, Serial No. 137,498

5 Claims. (Cl. 62—126)

My invention relates to evaporators for refrigerating machines.

It is an object of my invention to provide an improved evaporator of the type comprising a freezing chamber having refrigerated side walls and a shelf of relatively high heat absorbing capacity arranged between the walls for supporting freezing trays.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawing in which Fig. 1 is a front elevational view of a household refrigerator provided with an evaporator embodying my invention, and Fig. 2 is an enlarged perspective view of the evaporator shown in Fig. 1.

Referring now to the drawing, in Fig. 1, I have shown a household refrigerator comprising a cabinet 10 having a door 11 and provided with a removable top 12 on which is mounted a refrigerating machine comprising a motor and compressor casing 13, a natural draft air cooled condenser 14 and an evaporator 15. The evaporator 15 comprises a U-shaped wall portion 16 defining a freezing chamber and a refrigerated shelf 17 arranged within the freezing chamber. During the operation of the refrigerating machine gaseous refrigerant is compressed by operation of the motor and compressor within the casing 13 and is discharged through the condenser 14 where it is cooled and liquefied by the circulation of air over the condenser. The liquid refrigerant flows from the condenser through a connection 18 into a float valve chamber or receiver 19 and when a predetermined amount of liquid refrigerant has collected in the chamber 19 a float arranged therein rises and allows the liquid refrigerant to pass through a connection 20 into the wall portion of the evaporator 15. A portion of the liquid refrigerant is vaporized by the absorption of heat from the air within the cabinet 10 and liquid and gaseous refrigerant are discharged from the wall portion 16 into the shelf 17. The shelf 17 is provided with a header 21 formed in a vertical portion thereof which is maintained about half full of liquid refrigerant, so as to flood the passages extending from the header. The gaseous refrigerant collects in the header 21 above the level of liquid refrigerant therein and is withdrawn therefrom through a conduit 22 and returned to the casing 13.

The details of construction of the evaporator 15 are clearly shown in Fig. 2. The wall portion 16 which provides the side and bottom walls of a freezing chamber is constructed of inner

and outer metal sheets 23 and 24 respectively. An extended series conduit 25 having relatively few turns is formed by providing an indentation in the outer sheet 24. The inner and outer sheets are cut to the desired shape while flat, the inner sheet being provided with end portions 26 extending beyond the ends of the outer sheet 24 so that they may be bent over the edges of the outer sheet as shown. The indentation 25 is stamped in the outer sheet and the sheets are then secured together between the turns of the indentation and around the edges of the sheets by welding, brazing or in any other suitable manner, the end portions 26 being bent over the outer sheet 24 and the sheets being thereafter bent into the U-shaped form of the wall portion 16. Flanges 27 at the tops of the side walls are provided in order that the evaporator may easily be secured to the removable top 12 of the cabinet 10. The shelf 17 comprises upper and lower metal sheets 28 and 29 respectively. The sheets 28 and 29 are cut to the desired shape while flat, the sheet 28 being provided with end portions 30 which may be bent around the ends of the sheet 29 as shown at the front of the shelf and with side portions 31 providing upwardly extending flanges for securing the shelf to the side walls of the evaporator. At the rear of the shelf the header 21 is made of cylindrical form by providing complementary indentations in the sheets 28 and 29. The rear portion of the shelf indicated at 32, is bent vertically upwardly so that the header 21 is above the level of the shelf. The lower sheet 29 is provided with a plurality of indentations forming U-shaped conduits 33 communicating at both ends with the header 21 below the level of liquid refrigerant therein, a manifold 34 and a plurality of ducts 35 providing communication between the manifold and the conduits 33. The shelf 17 is secured within the freezing chamber by welding, brazing or otherwise fastening the flanges 27 to the sides of the inner sheet 23 of the wall portion 16. The connection 20 is provided at one end of the conduit 25 for admitting refrigerant thereto and a connection 36 is provided between the other end of the conduit 25 at one end of the manifold 34 so that refrigerant may be removed from the conduit 25 and admitted to the manifold 34 from whence it is directed in jets from the ducts 35 into the passages 33 to produce a circulation of liquid refrigerant therein.

The wall portions 16 are provided for cooling the air within the cabinet 10 and the conduit 25 is constructed with relatively few turns for containing refrigerant so that its heat absorbing capacity per unit area of wall surface will be relatively low. The heat absorbing capacity per unit area of the shelf 17 is relatively high since this shelf is provided with a plurality of closely spaced

refrigerant circulating passages and since the liquid and gaseous refrigerant injected through the ducts 35 produces a rapid circulation of liquid refrigerant contained in the passages 33. 5 The high heat absorbing capacity of the shelf insures quick freezing of water, desserts or the like placed in trays on the shelf.

During the operation of the refrigerating machine, liquid refrigerant is admitted to the evaporator 15 through the liquid line 20 and flows through the turns of the conduit 25 where some of the liquid is vaporized by the absorption of heat from the air surrounding the evaporator. The vaporized refrigerant and portions of liquid refrigerant are conveyed from the conduit 20 through connection 36 and flow into the manifold 34. Liquid refrigerant is maintained in the passages 33 of the shelf 17 and partially filling the header 21 and the liquid and gaseous refrigerant flowing from the manifold 34 through the ducts 35 in jets produces a rapid circulation of the liquid refrigerant in the conduits 33. This provides a freezing shelf of high heat absorbing capacity since superheating of the liquid refrigerant and the accumulation of gaseous refrigerant within the passages 33 is prevented. The gaseous refrigerant collects in the header 21 above the level of liquid refrigerant therein and is withdrawn and conveyed therefrom through the suction line 22 by operation of the compressor within the casing 13.

From the foregoing it is evident that I have provided an evaporator of simple and rugged construction having an air cooling portion and a freezing chamber within which is arranged a freezing shelf of high heat absorbing capacity.

While I have described my invention in connection with a household refrigerating machine, other applications will readily be apparent to those skilled in the art. I do not therefore desire my invention to be limited to the particular construction shown and described, and I intend in the appended claims to cover all modifications within the spirit and scope of my invention.

45 What I claim as new and desire to secure by Letters Patent of the United States is:

1. A refrigerant evaporator comprising sheet metal wall portions providing a freezing chamber, a shelf arranged within said chamber, means including a conduit and a refrigerant header for containing refrigerant to cool said shelf, said conduit communicating at both ends with said header and said header being arranged to contain liquid refrigerant to maintain said shelf conduit flooded with liquid refrigerant, means for admitting refrigerant to said evaporator, means including an extended conduit arranged in series between said shelf conduit and said refrigerant admitting means for conducting refrigerant over said wall portions, and means arranged between said extended conduit and said shelf conduit for directing refrigerant in a jet into said shelf conduit from said extended conduit to produce a circulation of liquid refrigerant within said shelf conduit, and means for conveying gaseous refrigerant from said header.

2. A refrigerant evaporator comprising sheet metal portions providing side and bottom walls of a freezing chamber, a shelf arranged between said side walls within said chamber, means including an extended conduit for containing refrigerant to cool said side walls, means includ-

ing a plurality of conduits for containing refrigerant to cool said shelf, a header secured to said shelf and arranged in communication with said plurality of conduits, means for admitting refrigerant to said extended conduit, means providing communication between said extended conduit and said plurality of conduits for conveying refrigerant from said extended conduit and for directing refrigerant in jets into said plurality of conduits to produce a circulation of liquid refrigerant therein, and means for conveying gaseous refrigerant from said header. 5

3. A refrigerant evaporator comprising sheet metal portions providing the walls of a freezing chamber, a shelf arranged between said walls 15 and having a vertical portion provided with a refrigerant header, a plurality of U-shaped conduits communicating with said header and arranged to contain refrigerant to cool said shelf, an extended conduit for containing refrigerant 20 to cool said walls, means for admitting refrigerant to said extended conduit, means providing communication between said extended conduit and said U-shaped conduits for conveying refrigerant from said extended conduit and 25 for directing refrigerant in jets into said U-shaped conduits to produce a circulation of liquid refrigerant therein, and means for conveying gaseous refrigerant from said header.

4. A refrigerant evaporator comprising sheet 30 metal portions providing side and bottom walls of a freezing chamber, means including an extending conduit having relatively few turns and arranged on said walls for containing refrigerant to cool said walls, a shelf arranged between said 35 walls and having a header at one end thereof and a plurality of U-shaped conduits each communicating at both ends with said header for containing liquid refrigerant to cool said shelf, means for admitting refrigerant to said extended 40 conduit, means providing communication between said extended conduit and said U-shaped conduits for conveying refrigerant from said extended conduit and for directing refrigerant in jets into said U-shaped conduits to produce a 45 circulation of liquid refrigerant therein, and means for conveying gaseous refrigerant from said header.

5. A refrigerant evaporator comprising sheet metal portions providing side and bottom walls 50 of a freezing chamber, a sheet metal shelf arranged between said side walls and having a vertical portion extending upwardly from one end thereof, means including a header within said vertical portion and a plurality of U-shaped 55 conduits formed within said shelf for containing liquid refrigerant to cool said shelf, means including an extended conduit having relatively few turns and formed within said walls for containing refrigerant to cool said walls, means for admitting refrigerant to said extended conduit, means including a manifold at the end of said shelf remote from said header and a plurality of ducts connecting said manifold and said U-shaped conduits for conveying refrigerant from 60 said extended conduit and for directing refrigerant in jets into said U-shaped conduits to produce a circulation of liquid refrigerant therein, and means for conveying gaseous refrigerant from said header. 65
